UNITED STATES PATENT OFFICE.

JAMES CRAWFORD, OF BOSTON, MASSACHUSETTS, ASSIGNOR TO JOSEPH H. YOUNG CO.,
OF BOSTON, MASSACHUSETTS, A CORPORATION OF MASSACHUSETTS.

DESIGN FOR A TRAP.

45,856.

Specification for Design.

Patented June 2, 1914.

Application filed April 14, 1914. Serial No. 831,836. Term of patent 7 years.

To all whom it may concern:

Be it known that I, JAMES CRAWFORD, a citizen of the United States, residing at Boston, county of Suffolk, State of Massachusetts, have invented a new, original, and ornamental Design for a Trap, of which the following is a specification, reference being had to the accompanying drawing, forming part thereof.

The figure is a perspective view of a trap showing my new design.

I claim:

The ornamental design for a trap, as shown.

JAMES CRAWFORD.

Witnesses:

LOUIS C. SMITH,

THOMAS J. DRUMMOND.
